PORTABLE GOLF CLUB HOLDER

Herbert L. Trautmann, 873A W. 15th St.,
Newport Beach, Calif.

Filed July 19, 1965, Ser. No. 86,192

Term of patent 14 years

(Cl. D34—5)

FIG.1

I claim:

The ornamental design for a portable golf club holder, substantially as shown.
